UNITED STATES PATENT OFFICE.

JULIEN PIETERS, OF PARIS, FRANCE.

ARRANGEMENT FOR EVOLVING DISTILLATION GASES IN VERTICAL RETORTS.

1,412,629.

Specification of Letters Patent. Patented Apr. 11, 1922.

Application filed July 1, 1920. Serial No. 393,293.

To all whom it may concern:

Be it known that I, JULIEN PIETERS, a subject of the King of Belgium, and a resident of 12, Rue de La Rochefoucauld, Paris, France, have invented new and useful Improvements in Arrangements for Evolving Distillation Gases in Vertical Retorts, of which the following is a specification.

The present invention relates to an arrangement for the evolution of the gases of distillation in vertical retorts of relatively great height, in which fine materials such as coal not easily permeable by the gas are treated. In this case the evolution of the gas through the mass of coal is comparatively difficult inasmuch as the suction of the exhausting apparatus is unable to exert its effect as far down as the bottom of the retort or even beyond a certain depth. The gases from the lower part of the retort being insufficiently exhausted, remain therefore for a certain time in the retort, becoming heated by contact with the walls, and therefore decomposed; alternatively the pressure of the gas becomes so great that a portion can escape directly through the refractory lining of the retort into the heating passages.

The arrangement for the evolution of distillation gas forming the subject of the present invention allows of obviating this disadvantage, by providing a complete extraction of the gas produced. The latter may be divided into two perfectly separate portions:

A first portion, comprising all the water vapour and a low proportion of combustible gas, is evolved at a temperature lower than that of the coking zone proper, in which the mass acquires a semi-liquid consistency, very impermeable to the gases and said portion of the gases clears a passage through the mass of coal, up to the top of the retort where it is easily exhausted by suction.

The second portion, which is formed in the lower part of the retort and comprises the great majority of the combustible gas is practically unable to pass through the coking zone, but is exhausted at different points in the height of the retort.

When, as in the case represented in the drawings, the retort is of great height, the evolution of gas at the top takes place through a fairly large number of openings distributed over the length of the retort and connected to a collecting main parallel to the

axis of the retort but on one side of the same. This collector may rest directly upon the brickwork thus forming the upper wall of the retort.

This arrangement offers the advantage of facilitating cleaning of the gas-escape openings by means of manholes suitably formed in the top of the collecting main.

The extraction of gas from the vertical part of the retort takes place in this case at the two ends which are unheated and therefore readily accessible.

In the annexed drawings:—

Figure 1 is a vertical section on the axis of a retort provided at its upper portion with a number of openings for the aspiration of gas, and three extraction passages on each of the unheated vertical faces.

Figures 2, 3 and 4 are transverse sections upon lines 2—2, 3—3 and 4—4 of Figure 1, through a number of vertical retorts arranged to form a battery and separated merely by a heating wall or pier.

The water vapour evolved at the top of each retort A, together with a part of the distillation gas, is aspirated through openings *a* formed at the top of the heating piers B, and passes into the collecting mains *b* located in pairs parallel to the retort and above the same; thence it flows into the stand-pipes *c* connected through a valve *d* to the exhausting main *d*; a stand-pipe *e* is provided upon the corresponding collector *b* at each end of the retort A on either side of the chimney *c* through which the material is admitted to the retort.

The greater portion of the combustible gas is evolved through the pipes *e* arranged in the two vertical unheated faces and at the lower part of the retort, above the level of the coking zone; these pipes are located in a collecting gallery *e'* and are connected to a vertical main *f* for each retort, leading to a common exhaustion pipe *g* through a valve *g'* for each collecting main *f*.

The two exhaustion pipes *d* and *g* are themselves connected to a common exhausting conduit which leads to the by-products plant.

What I claim is:

1. Means for the recovery of distillation gases from vertical retorts, comprising a large number of openings on the same level in the upper area of the retort, to collect a portion of the gas consisting of the water vapor and a small part of the combustible

- gas, in combination with openings located at different levels in the lower portions of the retort to collect the greater part of the combustible gas.
- 5 2. Means for the recovery of distillation gases from vertical retorts, comprising a large number of openings on the same level in the upper area of the retort, arranged in two series parallel to the longitudinal axis of the retort throughout its length, and two collecting mains parallel to the longitudinal axis of the retort, resting on the upper part of the retort and connected to the said two

series of openings, to collect a portion of the gas consisting of the water vapor and a 15 small part of the combustible gas, in combination with openings located at different levels in the lower portions of the retort to collect the greater part of the combustible gas.

20 In testimony whereof I have signed my name to this specification.

JULIEN PIETERS.
